United States Patent Office Action for U.S. Appl. No. 16/046,216, dated Jun. 17, 2019, 10 pages.

Primary Examiner — Rosemary K Tarcza*Assistant Examiner* — Nathaniel D. Buckner(74) *Attorney, Agent, or Firm* — Michael Best & Friedrich LLP(57) **CLAIM**

I claim the ornamental design for a pocket hole jig, as shown and described.

DESCRIPTION

FIG. 1 is a perspective view of a pocket hole jig showing my new design.

FIG. 2 is a back side view thereof.

FIG. 3 is a front side view thereof.

FIG. 4 is a right side view thereof.

FIG. 5 is a left side view thereof; and,

FIG. 6 is a top view thereof.

The broken lines in the figures depict portions of the article that form no part of the claimed design.
